(57) **CLAIM**

The ornamental design for a rear-steering scooter body, as shown and described.

DESCRIPTION

FIG. 1 is a front top perspective view of the rear-steering scooter body of the present invention showing our new design;

FIG. 2 is a rear top perspective view thereof;

FIG. 3 is a side elevational view thereof with the dotted lines depicting solely environmental structure and forming no part of the claimed design;

FIG. 4 is a top plan view thereof;

FIG. 5 is a side elevational view thereof;

FIG. 6 is a bottom plan view thereof;

FIG. 7 is a front end view thereof; and,

FIG. 8 is a rear end view thereof.
